Primary Examiner—Terry A. Wallace*Assistant Examiner*—C. Tuttle*Attorney, Agent, or Firm*—Royston, Rayzor, Vickery, Novak & Druce, L.L.P.**[57]****CLAIM**

The ornamental design for the combination headband and ponytail holder, as shown and described.

DESCRIPTION

FIG. 1 is a perspective view of a combination headband and ponytail holder according to the present invention;

FIG. 2 is a front elevational view thereof;

FIG. 3 is a back elevational view thereof;

FIG. 4 is a top and bottom plan view thereof; and,

FIG. 5 is a left side elevational view thereof, the right side elevational view being symmetrical thereto.

The broken line showing of the human form is for illustrative purposes only and forms no part of the claimed design.
